UNITED STATES PATENT OFFICE.

TEIJIN ODARKA, OF WEST ORANGE, NEW JERSEY.

TOY.

Application filed December 11, 1920. Serial No. 429,987.

To all whom it may concern:

Be it known that I, TEIJIN ODARKA, a subject of the Emperor of Japan, residing at West Orange, in the county of Essex and 5 State of New Jersey, have invented new and useful Improvements in Toys, of which the following is a specification.

This invention relates to toys and has for its primary object the provision of a novel 10 device of this character which will include an object or figure capable of being tilted upon and spun around a supporting axis, the said object or figure being formed and so balanced that a state of neutral equilibrium is automatically restored after the 15 object has been moved from what can be stated to be a normal or approximately normal position.

A further object of the invention is to 20 provide a toy from which considerable amusement and enjoyment can be derived and one which may be colored in a manner that will cause the toy to present a pin-wheel effect when the same is spun around 25 a supporting axis.

A still further object of the invention is to provide a toy that can be made in a variety of different figures, each characterized by a functioning action that will give rise 30 to a great range of pleasure.

With the above and other objects in view which will appear as the nature of the invention is better understood, the same consists in the improved construction and novel 35 arrangements of parts which will herein-after be fully described and particularly pointed out in the claim.

In the accompanying drawings, has been illustrated, a single and preferred form of 40 the invention, it being, however, understood that no limitations are necessarily made to the precise structural details therein exhibited, but that changes, alterations and modifications within the scope of the claim may 45 be resorted to when desired.

Figure 1, is a perspective view of the toy.

Figure 2 is a vertical longitudinal section therethrough.

For the purpose of illustration, I have 50 shown a grotesque figure 5 in the form of a boy, the same having a body portion 6, arms 7-7, a head 8 and legs 9-9. The legs are in a straddle position or the same are spread apart and in line with the vertical center or 55 at the crotch of the figure is a depending

eye 10. Interposed between the eye and the crotch and secured to the figure 5 is an arcuate weight 11. The construction of the device is such that the eye 10 is adapted to be accommodated by the fixed axis 12 of a 60 handle 13 and through the arrangement of the legs 9-9 of the figure, portions thereof are disposed low enough to throw the center of gravity of the body below said axis. This causes the figure to normally occupy a state 65 of neutral equilibrium and it permits the figure to be shifted and to assume states of staple and unstaple equilibrium respectively. It further provides a means whereby the object can be spun in pin-wheel fashion around 70 the supporting axis 12. The axis 12 is in the form of a nail, the shank of which is removably extended into a passage 14, in the handle 13. The outer end of the nail is provided with a head 15 that serves as a stop to 75 prevent the figure from flying off of its axis when the toy is in operation. The construction of the handle 13 is such that the nail or axis 12 can be freely drawn out of the handle and passed through the eye 10 of the figure 80 5 when it is desired to assemble the parts. The arrangement provides means whereby the toy can be arranged to assume a comparatively compact package for shipment or storage.

The figure 5 can be struck from fiber board, metal or any suitable well known material and the same may be painted in a different manner on its opposite sides. For instance, the side toward the operator may be 85 painted in a mixture of blue and other colors and the side away from the operator may be red and a number of other harmonizing colors. This makes the toy reversible so that either side may be presented to the view of 90 the child or operator. By distributing the colors on each side of the figure with a certain measure of discretion, the object when spun around the axis 12, presents a pin-wheel effect.

The weight 11 co-acts with the legs 9-9 of the figure so as to establish a perfect balance of the latter upon its axis and to maintain normal or neutral equilibrium when the handle 13 is held in the hand of the operator. By tapping the figure on either side, it follows that the same is spaced in oscillatory motion and incident thereto the object 105 respectively attains states of staple and unstaple equilibrium. By striking the object 110

hard enough the same is made to spin entirely around the axis 12 and rotation of the object will continue for a rather long interval on account of the arrangement of the weight 11 and the legs 9-9.

While I have shown just one form of making the toy, I of course do not wish to be limited in this respect. For instance, instead of the figure of a boy as shown in the accompanying drawings, the same may be in the form of a see-saw or many like arrangements can be resorted to. In each instance, the functioning of the toy will of course remain the same as in the first instance.

What is claimed as new is:—

A toy comprising a handle having a fixed axis, an object supported from said axis and provided with means to permit it to be spun around said axis and to rock thereon, said means including an eye member extending from the base of the object and freely embracing said axis, the object including a portion normally rising above the axis and portions arranged to extend downward and straddle the axis.

In testimony whereof I have affixed my signature.

TEIJIN ODARKA.
